UNITED STATES PATENT OFFICE.

GEORGE P. AITCHESON, OF ALEXANDRIA, VIRGINIA.

DESIGN FOR A BADGE.

SPECIFICATION forming part of Design No. 33,354, dated October 16, 1900.

Application filed September 17, 1900. Serial No. 30,360. Term of patent 3½ years.

To all whom it may concern:

Be it known that I, GEORGE P. AITCHESON, a citizen of the United States, residing at Alexandria, in the county of Alexandria and State 5 of Virginia, have invented and produced a new and original Design for a Badge; and I do hereby declare the following to be a full, clear, and exact description of the same, reference being had to the accompanying drawings, forming a part thereof.

In the accompanying drawings, Figure 1 is a front view of my design for a badge. Fig. 2 is a vertical section on the line 2 2 of Fig. 1, and Fig. 3 is a transverse section on the line 15 3 3 of Fig. 1.

My design consists, essentially, of a body portion 1, having the appearance of a bucket or pail. At the upper end and at opposite sides thereof the body 1 has lateral projections 2, with which the bail-like member 3 joins, which member extends vertically from the body portion and has a central handle ornamentation 3^a. The body 1 terminates in a dome-shaped top 4, the crown of which extends 20 vertically upward and has a mouth shape, (indicated by 5.) The body 1 at one side has a raised part 6, shaped like a bracket, and a vertically-disposed ornamentation 7, having the shape of an ordinary table-knife, the blade 25 portion of which has a broken and notched cutting edge. The said ornamentation 7 has the appearance of a worn-out table-knife. At the opposite sides the body 1 has a similar bracket-like ornamentation 8, which merges

with the vertically-projecting ornamentation 35 9, having the shape of a badly-broken table-fork.

My design in its complete form also includes the inverted-cup representation 10, the bottom edge of which is shown as raised slightly 40 above the mouth 5, and the said lower edge has a roughened or broken appearance, the handle member 10^a of the cup also appearing as broken.

11 11 designate ornamentations extending 45 pendently from the bottom of the cup, said ornamentations having the appearance of matter running from the cup over the top and front of the body 1.

My complete design as viewed in front view 50 has the appearance of a workingman's dinner-pail, with a knife and fork upon the face thereof, the cup slightly lifted above the mouth, and all of the several parts so shaped as to represent a dilapidated workingman's 55 dinner-pail.

In horizontal section the body of my badge has a convex shape, as best shown in Fig. 3.

Having thus described my invention, what I claim is—

The design for a badge, substantially as shown and described.

In testimony whereof I affix my signature in presence of two witnesses.

GEORGE P. AITCHESON.
